REFILL CARTRIDGE FOR LIPSTICK
HOLDERS

Claudine Reine Sherman, New York, N. Y.

Application September 27, 1950, Serial No. 186,943

9 Claims. (Cl. 206—56)

1

This invention relates to refill cartridges for lipstick holders.

An object of the invention is to provide an improved refill cartridge for a lipstick holder, which is so constructed and arranged that a user may easily and quickly insert the lipstick in the holder without experiencing smudged fingers, clothing, etc.

Another object of the invention is to provide an improved refill cartridge according to the above, which has few parts and is of simple and economical construction.

A further object of the invention is to provide an improved refill cartridge as characterized above, which is easy and convenient to open and to use, while at the same time constituting a secure package which will not accidentally come apart and expose the lipstick.

In accomplishing the above objects I provide an improved refill cartridge comprising a novel assemblage of lipstick and resilient deformable cup receiving the base of the lipstick, the said cup having an outer diameter of a size enabling it to be received in a lipstick holder. By virtue of the cup being resilient and deformable it will accommodate itself to slightly different diameters of openings in the lipstick holder, and will be securely retained in the holder, preventing accidental dislodgment of the lipstick from the holder.

In conjunction with this novel assemblage I provide a tubular housing which is preferably transparent, enclosing the lipstick and engaging the resilient cup whereby the latter and lipstick are removably mounted in the housing. To complete the organization I provide a removable cap which encloses the cup and surrounds the portion of the housing which engages the cup, thereby to produce a complete package which protects the lipstick against damage, while at the same time enabling it to be readily inserted in the holder upon removal of the cap.

Besides the lipstick itself there are only three other parts, two of said parts constituting the outer components of the package while the third part, i. e. the resilient cup, constitutes the mounting means by which the lipstick is supported in the holder.

To apply the lipstick to the holder, the user merely grasps the housing and removes the cap therefrom, and then inserts the exposed resilient cup in the opening of the lipstick holder. The user then pulls the housing away from the holder, exposing the lipstick whereupon it may be readily retracted and/or used. In the entire operation

2

it is not necessary at any time for the fingers to come in contact with the lipstick itself, and thus smudging of the fingers and clothing is avoided.

The three parts of the cartridge mentioned above may be readily molded of plastic in simple multi-cavity molds, thereby enabling these parts to be economically produced in large quantities. Thus the cost of the refill cartridge will be low, enabling it to be retailed at an attractive, popular price.

Other features and advantages will herein-after appear.

In the accompanying drawings:

Figure 1 is an axial sectional view of an improved refill cartridge for a lipstick holder, made in accordance with the invention.

Fig. 2 is a view of the cartridge in elevation, with cap removed, about to be inserted in a lipstick holder, which latter is shown in section.

Fig. 3 is an axial sectional view of the refill cartridge and lipstick holder, with the cartridge inserted.

Fig. 4 is a view partially in elevation and partially in perspective, showing the housing or casing removed from the cartridge, with the lipstick being retained on the holder.

Fig. 5 is an enlarged detail in section, showing interengaging portions of the components which make up the cartridge.

Fig. 6 is a side elevational view of a cup for holding the lipstick, illustrating a modification of the invention.

Referring to Figs. 1 and 2, the improved lipstick refill cartridge of the present invention comprises a resilient or deformable cup 10 having cylindrical side walls 10a and a beveled wall portion 11, the latter extending around a flat bottom 12.

The cup 10 may be made of any suitable material to render it readily deformable or yieldable. For example, it may be made of paper or a paper-like product such as cardboard, foil, etc., or as at present preferred, it may be molded of suitable plastic such as polyethylene (polymerized ethylene) which is substantially nonrigid and yielding when formed into various shapes.

Preferably, as shown in Figs. 1, 3 and 5, the rim portion 13 of the cup is provided with an outwardly disposed projection, shown here as a flange 14, forming somewhat of a lip. If desired, instead of the flange 14 other shapes or projections such as lugs or nibs 14a (Fig. 6) may be used. The cup 10 is adapted to receive and carry a lipstick 15 which may be formed of the usual composition containing wax, coloring matter, etc.

As seen in Figs. 1 and 3, the base 16 of the lipstick is disposed in the cup 10, being snugly fitted thereto whereby it will be retained against accidental removal. In this connection it should be noted that where the cup 10 is formed of a plastic material such as polyethylene which is relatively nonporous, the vacuum effect resulting from moving of the lipstick 15 out of the cup 10 will serve to retain the lipstick in the cup, thus preventing accidental dislodgment of the lipstick.

Surrounding the lipstick 15 and adapted to engage the flange 14 of the cup 10 is a removable tubular housing 17 having a closed end 18, the other end 19 of the housing being open and provided with a counterbore, forming an internal shoulder 20. The counterbore portion or edge of the housing 17 is adapted to receive and frictionally fit the flange 14 of the cup 10, with the shoulder 20 of the housing engaging the top edge of the cup and positioning the cup with respect to the housing.

The housing 17 is relatively rigid, and may be made of metal, or polystyrene plastic (polymerized styrene monomer) or any other suitable material. Preferably it is transparent so that the color or shade of the lipstick may be observed by the customer without removing the housing.

Enclosing the cup 10 and lower portion of the housing 17 is a removable tubular cap 21, having a bottom wall 22 and having on its side wall an internal shoulder 23 for engagement with the bottom edge of the housing 17 whereby the cap will have a predetermined position thereon. Above the shoulder 23 the cylindrical wall of the cap 21 is made to frictionally fit the exterior of the housing 17 so that the cap will be securely held on the housing, yet may be readily removed.

Preferably, as shown in Fig. 5, the shoulder 23 of the cap engages the flange 14 of the cup 10, thereby tending to prevent separation of the cup from the housing 17 during storage or transportation of the cartridge.

Referring to Figs. 2, 3 and 4 a lipstick holder 24 is shown, comprising a casing 25 carrying a cup 26 which is axially retractable in a casing. The cup 26 may be retracted or extended in the casing 25 by any suitable means (not shown) well known in the art. When the cup 26 is extended as shown in Figs. 2 and 3, it is in position to receive the cup 10 of the refill cartridge for the purpose of providing the holder 24 with a new lipstick.

When a user desires to insert the lipstick 15 in the holder 24, she first removes the cap 21, after which she inserts the cup 10 of the cartridge in the cup 26 of the holder. Such insertion is facilitated by the bevel 11 surrounding the bottom 12 of the cup 10, since the bevel results in a smaller diameter being presented to the cup 26. During this operation, the user grasps the housing 17, and at no time are the fingers in contact with the lipstick 15. When the cup 10 of the cartridge has been firmly seated in the cup 26 of the holder, the housing 17 is pulled away and removed, as shown in Fig. 4, exposing the lipstick 15.

If desired, the cup 10 may be provided with an external circular bead 14b midway between its top and bottom, as shown in Fig. 6, to provide a more secure seating of the cup in the holder. It will be observed that, upon insertion of the cup 10 in the holder, the compressing of the center portion of the cup as a result of such bead will cause the inside walls of the cup to move inward and more firmly hold the lipstick.

I have found that by virtue of the cup 10 being made resilient as by forming it of a yieldable material such as paper, foil, or polyethylene plastic, it will readily accommodate itself to the inside diameter of the cup 26 even though it might be very slightly larger than the latter cup. Also, when the cup 10 of the cartridge has been fully inserted in the cup 26 of the lipstick holder, the cartridge cup will be firmly retained in the holder, securely mounting the lipstick 15 and preventing inadvertent dislodgement thereof. If, as is sometimes the case, the cup 26 of the holder has inwardly projecting retainer nibs, the yieldable cup 10 will conform itself to the shape of the nibs without difficulty. Thus not only is the insertion of the cartridge in the holder facilitated by the nonrigid construction of the cup 10, but retention of the cartridge in the holder is aided.

By making the housing 17 of a transparent plastic such as polystyrene or the like the color of the lipstick 15 may be observed through the housing, so that the purchaser may accurately determine the exact shade that she desires.

Referring to Fig. 4, it will be understood that when the lipstick 15 has been inserted in the holder it may be retracted completely in the holder in the usual manner, as is well understood.

The improved refill cartridge of the present invention is thus seen to be particularly advantageous in enabling a user to easily and quickly provide a refill for her lipstick holder. In the process of inserting the refill, the lipstick will not come in contact with the fingers of clothing of the user, thus positively eliminating smudging. Moreover, the protection afforded the lipstick by the housing 17 is of considerable importance in that it prevents damage, marking or deformation of the lipstick. When it is considered that lipsticks are usually quite susceptible to marking or damage, being wax-like and of soft consistency, this latter is an important consideration.

By virtue of the provision of the resilient cup 10 the operation of inserting a second refill, made according to the invention, in the lipstick holder is greatly facilitated, since removal of the cup 10 of the previous lipstick is very easily accomplished. Such removal may be readily effected for example by the use of any suitable sharp or pointed instrument, eliminating the messy job of digging out the remains of the lipstick in pieces, as was heretofore necessary.

The improved lipstick refill cartridge of this invention is also advantageous in that the combination of the housing 17, cup 10, and cap 21 provides an airtight container for the lipstick 15, preventing loss of essential oils, change in physical appearance, etc.

Variations and modifications may be made within the scope of the claims and portions of the improvements may be used without others.

I claim:

1. A refill cartridge for a lipstick holder, comprising a cup having an outside diameter of a size enabling it to be received in the lipstick holder; a lipstick having its base inserted in said cup; a tubular housing closed at one end, the other end of the housing receiving the rim of said cup and having a frictional fit therewith, said housing having an internal shoulder engaging the edge of the cup to position the latter in the housing; and a removable cap surrounding said cup and said other end of the housing and having a frictional fit with said end whereby the cap may be readily

removed to expose the cup for insertion in the lipstick holder.

2. The invention as defined in claim 1, in which the cap has an internal shoulder engaging the edge of the said other end of the housing to position the cap on the housing.

3. The invention as defined in claim 1, in which the rim of the cup has an outwardly disposed projection engaging the said other end of the housing and also the shoulder in said housing.

4. The invention as defined in claim 1, in which the rim of the cup has an outwardly disposed peripheral flange engaging the said other end of the housing and also the shoulder in said housing, and in which the cap has an internal shoulder engaging the edge of the said other end of the housing to position the cap on the housing.

5. The invention as defined in claim 1, in which the cup is formed of molded polyethylene and is readily by hand pressure deformable to enable it to be inserted in lipstick holders having slightly different-sized openings.

6. The invention as defined in claim 1, in which the cup is formed of paper or paper-like material and is readily deformable by hand pressure to enable it to be inserted in lipstick holders having slightly different-sized openings.

7. The invention as defined in claim 1, in which the rim of the cup has an outwardly disposed projection engaging the said other end of the housing and also the shoulder in said housing, and in which the cap has an internal shoulder engaging the edge of the said other end of the housing to position the cap on the housing.

8. The invention as defined in claim 7, in which

the internal shoulder of the cap engages the outwardly disposed projection of the cup, thereby tending to prevent dislodgement of the cup in the housing.

5. 9. A refill cartridge for a lipstick holder, comprising a cup readily deformable by hand pressure, having an outside diameter of a size enabling it to be received in the lipstick holder; a lipstick having its base inserted in said cup; a tubular housing closed at one end, the other end of the housing receiving the rim of said cup and having a frictional fit therewith, said housing having an internal shoulder engaging the edge of the cup to position the latter in the housing; and a removable cap surrounding said cup and said other end of the housing and having a frictional fit with said end whereby the cap may be readily removed to expose the cup for insertion in the lipstick holder.
